[57] CLAIM

The ornamental design for combined cap and end plug structure for extrusion tubes and the like, as shown and described.

DESCRIPTION

FIG. 1 is a top front perspective view of a combined cap end plug structure for extrusion tubes and the like, showing my new design, the top rear perspective view being a mirror image thereof; the fragmentary broken lines indicating an extrusion tube are shown for illustrative purposes only;

FIG. 2 is a top plan view thereof; and

FIG. 3 is a side elevational view thereof, the opposite side being a mirror image thereof.

The bottom plan view is conventional.
